CIGARETTE AND CIGAR HOLDER

Raymond J. Cloutier, New Bedford, Mass., assignor of one-half to Margaret M. Cloutier, New Bedford, Mass.

Application March 20, 1943, Serial No. 479,931

1 Claim. (Cl. 131—175)

This invention relates to new and useful improvements in cigarette and cigar holders and more particularly to such a holder in which the cigarette is entirely enclosed and from which ashes cannot fall onto the clothes of the wearer.

An important object of the present invention is to provide a cigarette and cigar holder which can be used during blackout conditions in war time inasmuch as the fire or flame of the cigarette cannot be seen due to its sheltered position.

Another important object of the invention is to provide a cigarette and cigar holder which is not only useful during blackout conditions in war time, but has the paramount factor of safety in that should it be accidentally dropped on a bed or elsewhere there is very little chance of a conflagration ensuing.

Another important object of the invention is to provide a cigarette and cigar holder in which a cigarette or cigar can be lighted without the flame of the igniting element being seen.

Other objects and advantages of the invention will become apparent to the reader of the following description.

In the drawings—

Figure 1 is a side elevational view of the holder.

Figure 2 is a longitudinal sectional view through the holder.

Figure 3 is a transverse sectional view on the line 3—3 of Figure 2.

Figure 4 is a transverse sectional view taken substantially on the line 4—4 of Figure 1.

Figure 5 is a bottom plan view of the holder with the slide removed.

Figure 6 is a side elevational view of the mouth-piece.

Referring to the drawings wherein like numerals designate like parts, it can be seen that numeral 5 denotes a mouthpiece having a collar 6 protruding therefrom and around which is a stop shoulder 7. This collar 6 is adapted to be disposed in a tube 8 of plastic or any other suitable material in order to shelter a cigarette 9, or in fact a cigar. This smoking element 9 has its butt end disposed into a socket 10 protruding from the mouthpiece 5.

A perforated cap 11 is provided for the outer end of the tube 8.

The bottom of the tube 8 has a block 12 extending longitudinally thereof and having a slide-way 13 therein for receiving a slide 14, it being observable in Figure 3, that the bottom of the block 12 has a narrow slot 15 therein through which a reduced portion 16 of the block 14 is dis-

posed, the bottom portion 17 of the block 14 contacting the flat bottom side of the block 12. One end of the slide 14 has a flanged head 18 preferably provided with corrugations 19 to prevent finger slippage. It will be noted that the block 14 and the head 18 are properly dimensioned to space the same below the tube 8 sufficiently to permit said block and head to clear the shoulder 7 on the mouthpiece 5.

Suitably secured to the bottom side of the tube 8 within the confines of the block 12 is a replaceable strip of abrasive material 20 against which a match can be struck. Preferably the block 12 is provided with tongues 12' for supporting the side edges of the strip 20.

At the outer end of the tube 8, the tube is formed at its bottom side with an opening 21.

It can now be seen that by grasping the head 18 of the slide 14, the slide can be moved toward the right in Figure 2. The slide can be removed and a match inserted in the slot 15, scratched against the abrasive surface 20 and quickly inserted through the opening 21 to ignite a cigarette 9. This can be accomplished without any flare from the match flame.

Obviously, the holder is capable of being taken apart into a number of pieces for the purpose of cleaning, dumping of ashes, etc.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A cigarette and cigar holder comprising a mouthpiece adapted for the insertion of one end of a cigarette therein, a tube extending from the mouthpiece for enclosing the cigarette, a hollow structure on the bottom of the tube having a bottom slot for introducing a match into said structure, said tube having an opening communicating the interior of the tube with the interior of the hollow structure whereby a cigarette may be lighted in the tube by a match introduced through said structure, a slideable closure for the hollow structure fitting in the same, and a match scratcher in the hollow structure disposed between the closure and said tube for covering by the closure, said slideable closure being provided with a finger-engageable head.

RAYMOND J. CLOUTIER.
